CLAIM

I claim the ornamental design for a multi-bone themed baking pan, as shown and described.

DESCRIPTION

FIG. 1 is an isometric view of a multi-bone themed baking pan showing my new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof; and,

FIG. 7 is a rear elevation view thereof.
